US00D959254S

(12) **United States Design Patent** (10) Patent No.: **US D959,254 S**
(45) Date of Patent: **** Aug. 2, 2022**

(54) **ACCESSORY FOR DRILLING TOOLS**

(71) Applicant: **OLIVIER INDUSTRIE NV**, Rumbeke (BE)

(72) Inventor: **Gerdi Vankeirsbilck**, Rumbeke (BE)

(**) Term: **15 Years**

(21) Appl. No.: **35/510,417**

(22) Filed: **Aug. 27, 2020**

(80) **Hague Agreement Data**

Int. Filing Date: **Aug. 27, 2020**

Int. Reg. No.: **DM/210319**

Int. Reg. Date: **Aug. 27, 2020**

Int. Reg. Pub. Date: **Sep. 25, 2020**

(30) **Foreign Application Priority Data**

Mar. 26, 2020 (EM) 007774716-0001

(51) **LOC (13) Cl.** **08-01**

(52) **U.S. Cl.**

USPC **D8/396**

CPC **F16D 1/04** (2013.01)

(58) **Field of Classification Search**

USPC ..... D8/394-396, 356, 383; D13/153-155; D15/138-140; 24/16 PB, 17 AP, 30.5 P, 24/30.5 S, 300-302, 339; 285/383, 404, 285/344, 317, 382.7, 417; 403/305, 306, 403/362

CPC F16D 1/04; Y10T 279/17821
